Patented July 13, 1965

201,637

CABLE CLAMP

L. E. Lindsey, 222 Vista Ave., Pasadena, Calif.

Filed Nov. 10, 1964, Ser. No. 82,545

Term of patent 14 years

(Cl. D54—1)

FIGURE 1 is a top plan view of a cable clamp embodying my new design;

FIGURE 2 is a side elevational view from the lower side of FIGURE 1;

FIGURE 3 is an end elevational view from the left hand of FIGURE 2;

FIGURE 4 is a bottom plan view;

FIGURE 5 is a side elevational view from the top side of FIGURE 1;

FIGURE 6 is an end elevational view from the left hand end of FIGURE 5; and

FIGURE 7 is a longitudinal sectional view taken along line 7-7 on FIGURE 1.

I claim:

The ornamental design for a cable clamp, as shown.
